UNITED STATES PATENT OFFICE.

GEORGE E. DAVIS, OF DUBUQUE, IOWA.

POWER-HAMMER.

SPECIFICATION forming part of Letters Patent No. 726,879, dated May 5, 1903.

Application filed October 4, 1902. Serial No. 125,975. (No model.)

To all whom it may concern:

Be it known that I, GEORGE E. DAVIS, a citizen of the United States, residing at Dubuque, in the county of Dubuque and State of Iowa, have invented certain new and useful Improvements in Power-Hammers, of which the following is a specification.

This invention relates to improvements in power-hammers; and the main object of my invention is the provision of a novel construction of a power-hammer which is so constructed as to be readily taken apart or assembled, thus producing a machine which is readily transported in "knockdown" shape, and thus overcoming the objections to power-hammers in general use.

To attain these objects, the invention consists of a power-hammer embodying novel features of construction and combination of parts, substantially as disclosed herein.

In the accompanying drawings, Figure 1 is a perspective view of the entire power-hammer assembled ready for use. Fig. 2 is an enlarged side elevation of the upper portion thereof. Fig. 3 is a detail side elevation of the hammer and connecting-rod. Fig. 4 is a detail perspective view of the base and supporting-standards with the hammer and anvil removed. Fig. 5 is a sectional view taken 30 through the hammer-guiding yoke and a portion of the standards. Fig. 6 is a perspective view of the base detached. Fig. 7 is a sectional view through the base and the lower ends of the rear tubular standards. Fig. 8 is a sectional view through the forward portion of the forward standards. Fig. 9 is a sectional view through the base-plate and one of the tubular standards to show the connection therebetween; and Fig. 10 is an enlarged detail view of the plate 3, showing the bearings for the frame 19.

Referring to the drawings, the numeral 1 designates the base of the machine proper, which is provided with four projections or bosses 1^a, surrounding which are mounted and secured, by means of bolts, the four tubular standards 2, which have their upper ends surrounding similar projections or bosses 2^a upon the under side of plate 3, said plate being secured upon the standards by means of the long bolts 3^a, extending through the same, the base, and tubular standards,

and fastened with nuts 4. Formed integral with the base, near the rear portion thereof and projecting upward therefrom, are the 55 alined eyed lugs 5, in which is pivotally mounted the bail or foot-lever 6, which is adapted to surround the base of the anvil 7. The purpose of this lever is to operate the combined tightener and brake-lever (herein 60 after described) by means of the hooked rod 8, having its lower end connected to said bail and its upper hooked end engaging the eyed ends 9 of said combined tightener and brake-lever.

Upon the top of the forward end of the base 1 I place the anvil 7, which is provided in its top with a lateral groove 10, in which is movably mounted the hard contact-block 11.

Formed integral and extending upward 70 from the plate 3 are the two standards 12, which with the upper castings 13 form journals or bearings for the shaft 14, upon which is mounted a pulley 15, which receives motion from the belt 16. Pivottally secured to 75 the plate 3 by means of box-caps 13' and the depressions 18 beneath the same and inclined outwardly is a substantially U-shaped frame 19, which is provided with the inclined rectangular opening 20, in which is adjustably 80 secured the rectangular rod or bearing 21, having a bifurcated upper end 22, in which is journaled a tension-pulley 23.

The top plate 3 is provided with depressions 18^a for receiving the trunnions 18^b of the 85 frame 19, these depressions being upon the opposite side from the depressions 18 in same, Figs. 1 and 4, in order that the frame 19 may be reversed to admit of running the belt in the opposite direction when it is desired to 90 place the machine in a necessary position relative to the location of the line-shaft from which the machine is driven. This reversible feature is novel and valuable and possessed by no other trip-hammer.

In order to keep the belt at the proper tension, the pulley 23 is pressed into contact with the belt 16 by pressing downward the bail 6, connected with the hooked rod 8, which in turn depresses the combined tightener and 100 brake-lever 19, where connected at its eyed end 9. Upon the lower end of the U-shaped frame 19 is attached a friction-block 24, which engages with the widened flanges of the pul-

ley 15, acting as a brake upon the same by means of the tension of the coiled spring 25, which is attached at one end of the inclined terminus of the U-shaped lever 19 and at the 5 other end of the adjustable hooked bolt 26, which in turn extends through the bar 27, supported upon the inverted pedestal 28, which depends from the under side of the plate 3 and is fastened thereto by the bolt 29.

10 Carried upon the outer end of the shaft 14 is a disk 30, in which is provided a slot 31, in which is adjustably fastened a pitman 32. In order to determine the length of stroke of the hammer, the pitman is fastened in the groove 15 at a greater or less distance at either side from the center of the disk by the nut 33, attached to the bolt 34, extending through wrist-pin 35, upon which the pitman is pivoted. This pitman is tubular and has slidingly 20 mounted therein a telescoping rod or connecting-link 36, which has its lower end connected to a clamp 37, which surrounds the substantially U-shaped spring 38 at its center. The lower ends 39 of this leaf-spring are curved 25 outwardly and are forced outward by means of the spring tension, thus holding the pivoted links 40 in oppositely-spread positions, so as to render elasticity to the hammer-head 41, which is provided in its lower end with a slot, 30 in which is removably fitted the hammer-die 41', which is generally of a harder material than the head, and thus produces a hammer which when broken or mashed can be readily removed. This hammer-head is provided 35 with two opposed vertical slots 43, which are adapted to slidingly engage the removable guide-plates 44, secured in the forward end upon the outer face of the yoke 45 by means of bolts 46. This yoke comprises substantially the two outwardly-inclined arms 47, 40 whose ends 48 are provided with the curved faces 49 and the openings 50 to receive the bolts 51 and allow the clamp-plates 52, which are provided with similar opposed curved 45 faces 53, to engage the two forward tubular supports or standards, thus holding the yoke at the desired adjustment.

From this description, taken in connection with the drawings, it is evident that I provide a power-hammer which is readily taken apart and made ready for transportation, and which after being received in the knockdown form is very easily and readily assembled for operative position.

55 My power-hammer is operated and controlled as follows: The belt 16 runs loosely over the pulley 15, and when it is desired to set the hammer in motion the foot-lever or bail 6 is depressed, which rocks or tilts upon 60 its trunnions the frame 19, thus releasing the break-block 24 from the pulley 15 and at the same time forcing the tightener-pulley 23 against the belt 16, which in turn grips the pulley 15, thus rotating its shaft 14, thereby 65 transmitting a reciprocating motion to the hammer-head by means of its links, leaf-spring, pitman, and crank-disk, as hereinbe-

fore described. When the foot-lever is pressed lightly, the belt slips over the pulley at slight tension, which revolves the same 70 more slowly, (on account of slippage,) thus lessening the force of blow and speed of the hammer-head, and when the pressure is entirely removed from the foot-lever the tightener-pulley 23 becomes disengaged from the 75 belt, while at the same time the tension-spring 25 brings the brake-block 24 into contact with the widened flanges of the pulley 15, instantly stopping the motion of the same.

By constructing the base, the plate 3, and the tubular standards separate the long bolts 3^a can be readily secured in place to assemble these three main parts, but may be readily removed to allow the entire construction to be knocked down, the adjustably-mounted 85 hammer-guiding yoke being removably secured to the forward standards, so that the same is readily removed from connection with the tubular standards, thus allowing the machine to be separated in as many parts as is 90 desired for transportation.

What I claim as new, and desire to secure by Letters Patent, is—

1. In a power-hammer, the combination of a base, four vertical standards detachably secured to and projecting upward therefrom, a yoke adjustably secured to the two forward standards and projecting outward from said standards, guides carried by the outer end of said yoke, a reciprocating hammer mounted in the guides of said yoke, a leaf-spring connected to the hammer, a supporting-plate detachably secured upon the upper ends of said standards, and a mechanism mounted upon said plate and connected with the leaf-spring for reciprocating the hammer. 105

2. In a hammer, the combination of a base, an anvil, a series of four standards having their lower ends detachably secured to the base and projecting upward therefrom, a yoke 110 adjustable vertically on the forward pair of said standards, guides carried by its outer face above and to each side of the apex of the anvil, a hammer reciprocatingly mounted in said guides, oppositely-arranged and pivotally-mounted links carried by the hammer, a substantially U-shaped leaf-spring having its terminal connected to said links, a telescoping pitman connected to the upper central portion of the spring, a plate detachably 120 secured to the upper end of said standards supported thereby, and mechanism mounted upon said supporting-plate for operating the pitman to convey a reciprocating motion to the hammer. 115

3. In a power-hammer, the combination of a base, an anvil, a series of four standards having their lower ends adjustably secured at right angles to each other to the base, a yoke adjustable vertically on the forward pair 130 of said standards, guides removably secured to the outer face of said yoke, a hammer reciprocatingly mounted between said guides, oppositely-arranged and pivotally-mounted 125

links carried by the hammer, a substantially U-shaped leaf-spring having its terminals connected to the links and adapted to hold them extended, a telescoping pitman having its lower end connected to the central portion of the spring, a rectangular plate detachably mounted upon the upper ends of said standards, a pair of standards 12 carried upon the upper face of said plates, a shaft journaled in said standards 12, and a disk provided with a groove mounted upon the shaft and having the upper end of the telescoping pitman slidably mounted in said groove, and a power-transmitting means 15 mounted upon the shaft.

4. In a power-hammer, the combination of a base provided with four upwardly-projecting bosses, a series of four cylindrical standards having their lower ends surrounding said 20 bosses and removably secured to the base, an anvil mounted upon said forward projection of the base, a rectangular plate detachably secured to the upper ends of said standards a yoke provided with inclined arms having

curved faces upon their extreme ends to contact the forward pair of said standards, clamp- 25 plates adapted to be secured to the rear face of said standards to cause the ends of the inclined arms to be brought in close contact with the standards to hold the yoke adjust- 30 ably upon the standards, a pair of guide- plates detachably secured to the outer face of the yoke and projecting toward each other, a hammer provided with vertical slots 43 to receive the guide-plates so as to be slidably 35 mounted and guided by the yoke, a pair of oppositely-spread links pivotally secured to the hammer, a leaf-spring having its terminals secured to said links, and mechanism mounted upon the rectangular plate con- 40 nected to the leaf-spring for reciprocating the hammer.

In testimony whereof I affix my signature in presence of two witnesses.

GEORGE E. DAVIS.
